UNITED STATES PATENT OFFICE.

ALBERT D. GROVER, OF NEW YORK, N. Y., ASSIGNOR, BY MESNE ASSIGNMENTS, TO
AUTOSALES CORPORATION, A CORPORATION OF NEW YORK.

COIN-CONTROLLED MACHINE.

1,283,161.

Specification of Letters Patent Patented Oct. 29, 1918.

Application filed February 11, 1916. Serial No. 77,550.

To all whom it may concern:

Be it known that I, ALBERT D. GROVER, a citizen of the United States, and a resident of New York city, in the county of New York and State of New York, have invented 5 certain new and useful Improvements in Coin-Controlled Machines, of which the following is a specification.

My invention relates generally to coin-controlled machines and its object is to provide guard mechanism arranged near the coin-entrance slot to prevent the insertion of paper and like material into the coin-chute.

It has been found by actual experience that 15 coin-controlled vending machines, especially those of the type used in theaters, are frequently put out of commission by pieces of paper stuffed into the coin-chute through the coin-entrance slot. The coin-chute being thus clogged up, the deposited coin is prevented from reaching an operative position within the machine and is, therefore, lost to the intending purchaser.

To overcome the above difficulty I have 25 devised means arranged near the coin-entrance slot for normally closing the coin-chute, and adapted to be automatically unlocked and moved into open position by the coin as it passes through the coin-entrance slot.

In the preferred form of my invention the guard mechanism for the coin-chute comprises a gate which is normally held across the coin-chute and so closes the same, and a coin-actuated member which normally locks 35 the gate in closed position and is moved into releasing position by the inserted coin. The relative arrangement of the gate and the locking member is such that after the coin 40 has been inserted about half-way into the coin-chute and partly opened the gate, the locking member is automatically moved into position to move the gate fully into open position independently of the coin, whereby the latter is free to pass through the coin-chute.

The gate and associated locking or controlling member are automatically reset into guarding position at the end of each operation of the machine.

When my invention is applied to a vending 50 machine I provide additional means for automatically holding the gate-locking member in a position in which it is out of locking engagement with the gate and at the same time closes or obstructs the coin-en-

trance slot against the insertion of further coins, when the supply of goods in the magazine is exhausted. In this condition of the machine, the unlocked gate furnishes quick and ready means for determining whether 60 the machine is empty, as explained in detail later on.

The above and other objects and advantages of my invention will become apparent from a detailed description of the accompanying drawings, in which—

Figure 1 is a front elevation of a coin controlled vending machine embodying my invention, the front door being removed and the compartment partly broken away for the 70 sake of clearness, the parts being shown in normal position.

Fig. 2 is a top view in cross-section on line 2—2 of Fig. 1, the top plate being broken away to show the guard mechanism beneath.

Fig. 3 is a section approximately on line 3—3 of Fig. 1.

Fig. 4 is a fragmentary view in cross-section on line 4—4 of Fig. 1, showing a detail of the operative connection by means of 80 which the coin-actuated member for the coin-chute gate is moved into unlocking position at each operation of the machine.

Fig. 5 is a fragmentary view of the upper portion of the machine shown in Fig. 1, with the parts of the guard mechanism in operated position when the coin has been inserted approximately halfway.

Fig. 6 is a top plan view in section on line 6—6 of Fig. 5, the top plate being broken 90 away to show the operated position of the parts which comprise the guard mechanism.

Fig. 7 is a section on line 7—7 of Fig. 5.

Fig. 8 is a view similar to Fig. 6, showing the gate fully opened by the associated controlling member, after the coin has passed beyond the halfway position in Fig. 5.

Fig. 9 is a fragmentary view in section on line 9—9 of Fig. 10, looking in the direction of the arrows, showing the coin-entrance slot 100 closed by the locking member of the guard mechanism, when the supply of goods in the machine is exhausted; and

Fig. 10 is a longitudinal section on line 10—10 of Fig. 9, showing the parts in corresponding position.

While my invention is broadly applicable to coin-controlled machines of various types, for the sake of illustration I have shown my invention as applied to a coin controlled 110

vending machine especially adapted for use in theaters and like places where only machines of small dimensions are permissible of use.

- 5 The casing of the particular machine shown in the drawings comprises a front member A and a rear member B, which are hinged together at the bottom at 1. The top of the casing is formed by the plate 2 which 10 is provided with the coin-entrance slot 3. Any suitable means may be provided for locking the hinged sections of the casing together, such as the lock L, which is secured to the rear wall of the back section B and 15 which has suitable bolts adapted to engage the sides of the front section A.
- The casing is provided with a partition 4 which forms with the front section of the casing the magazine for containing the vend- 20 able packages. The wall or partition 4 has hinged thereto a plurality of shelves 5 of which two are shown in the present instance, although the number may be varied to provide any other capacity for the machine. 25 Each of the shelves 5 is adapted to support a package of goods. The hinged connections between the shelves and the plate 4 are shown at 6 and 7. The hinge 7 of each shelf 5 includes a crank arm 8 by means of which 30 the shelves are tilted into releasing position, one at a time, through engagement with the coin-controlled slide or bar 9 mounted on the right side wall of the casing. The vertically movable bar 9 is provided with a pair of re- 35 versely arranged angular slots 10 and 11, as best shown in Fig. 3. The upper slot 10 is formed with a vertical or rest portion 10^a from which extends upwardly and forwardly the tripping portion 10^b. The lower 40 slot 11 is formed with an upwardly and forwardly extending tripping portion 11^a from which projects upwardly the vertical rest portion 11^b. When the goods-supporting shelves 5 and actuating bar 9 are in normal 45 position, the crank pin 8 of the upper shelf 5 rests at the bottom of the vertical portion 10^a of slot 10, while the crank pin 8 of the lower shelf 5 rests at the bottom of the tripping or actuating portion 11^a of the slot 11. Conse- 50 quently, when the bar 9 is moved downwardly (by mechanism to be presently described), the angular portion 11^a of slot 11 rocks the lower shelf 5 downwardly and thereby releases the supported package. At 55 the end of its movement the bar 9 is in a position in which the crank pin 8 of the lower shelf 5 is at the bottom of the vertical portion 11^b of slot 11, while the crank pin 8 of the upper shelf 5 is at the bottom of the angular or tripping portion 10^b of slot 10. It will be understood that during this first 60 movement of the bar 9, the pin 8 of the upper shelf engages the vertical or neutral portion 10^a of the slot 10, which results in no movement of the upper shelf 5. During the

next or second downward movement of the bar 9, the tripping portion 10^b of the upper slot 10 will rock the upper shelf 5 downwardly into releasing position, while the previously tripped lower shelf remains in 70 tripped position owing to the engagement of its crank pin 8 in the vertical portion 11^b of the slot 11. The bar 9 is guided in its movements by the pins or studs 12 which engage in slots 13 of the bar. As an additional 75 guiding means I may also provide the bar 9 with a forwardly extending lug 14 which moves in close proximity to the front plate of the casing.

The bottom of the goods-magazine is 80 formed by a bracket member 15 secured to the lower portion of the front section A and engaging at its upper end with the lower flange 16 of the magazine wall 4, as shown in Fig. 3. The magazine with its supporting 85 shelves, as well as the actuating bar 9, are carried by the rear section B which is adapted to be secured to a suitable support, such as the back of a theater chair. Therefore, when the front section A of the casing is 90 opened the parts are not disturbed and are presented for ready inspection. The connection between the bracket member 15 and the magazine wall 4 is merely one of contact and does not interfere with the free and ready 95 opening of the front section A.

The bar 9 is held in actuated position by a spring 17 secured to the rear section B of the casing and provided with a head 18 adapted to enter successively the openings or notches 100 20, 21 and 22 in the rear edge of the bar 9, as best shown in Fig. 3. When the parts are in normal position, as shown in Figs. 1 and 3, the spring 17 engages the notch 20 of the bar 9. At the end of the first downward 105 movement of the bar 9, the head of the spring 17 engages the notch 21, while at the end of the second (and, in this instance, final) movement of the bar 9, the spring 110 engages the notch 22.

The actuating bar 9 is actuated by the hand-lever 23 through the medium of the deposited coin. The hand-lever 23 is pivoted at 24 to the rear wall of the section B of the casing and at its free end 25 extends 115 out of the casing through a slot provided for that purpose. A suitable spring 26 normally holds the lever in uppermost position and also serves to return the lever to normal position when released. The lever 23 is provided with an upper extension 27 having a pin 28 on which is pivoted the coin-actuated connecting pawl 29. At its lower end the pawl 29, which normally hangs by gravity in the position shown in Fig. 1, is provided 120 with a tooth 30 adapted to enter openings 31 formed in the rear edge of the bar 9 and thereby establish an operative connection between the hand-lever 23 and the bar 9. The pawl 29 is also provided with a stud 32 ex- 130

tending forwardly into alignment with the vertical coin-chute which is indicated as a whole by S. The stud 32 is so spaced from the lower edge 33 of the coin-chute that when a proper coin is deposited it is supported at the bottom of the coin-chute between the edge 33 and the stud 32. When the coin strikes the stud 32 it swings the pawl 29 outwardly until the tooth 30 engages in the lower slot 31 of the bar 9. This forms an operative connection between the bar 9 and the hand lever 23 through the medium of the coin-controlled pawl 29. When, therefore, the hand-lever 23 is pulled down after the proper coin has been deposited, the bar 9 is pulled down at the same time. The extent of movement of the hand lever 23 is limited by the slot through which the outer end 25 extends. So that, when the hand lever 23 has reached the end of its downward movement, the lower shelf 5 has been tripped, as above described, and the package of goods is delivered to the supporting bracket 15, whence it may be removed by the purchaser through an opening provided for that purpose in the left side of the casing.

During the downward movement of the hand lever 23, the distance between the lower edge 33 of the coin-chute S and the stud 32 of the pawl 29 increases until the coin falls from between those two supports. This automatic ejection of the coin does not take place, however, until after the engagement between the tooth 30 and the bar 9 has been positively assured. The pawl 29 is guided in its swinging movements by the offset extension 34 formed on the hand lever 23.

The foregoing construction of magazine and coin-controlled delivery mechanism does not in and of itself form part of my present invention, as it is the subject-matter of my co-pending application, Serial No. 877,647, filed December 17, 1914, and I have herein set forth the above described construction of magazine and delivery mechanism merely for the sake of illustration and not by way of limitation of my invention. So far as the guard mechanism of my invention is concerned, the coin-controlled delivery mechanism of the vending machine to which it is applied may be of any approved construction. In the broad aspect of my invention I would, therefore, refer to the bar 9 as a mechanism adapted to be operated through the medium of the deposited coin, and such description applies to any suitable mechanism of that kind.

The particular embodiment of my new guard mechanism shown in the accompanying drawings comprises a gate 35 and a locking or controlling member 36. Both of these members are slidably mounted beneath the plate 37 which is rigidly held in place below the top or cover 2 of the casing. The gate 35 has a slot 38 in which engages the lug 39 extending downwardly from the supporting plate 37. At its inner end the gate 35 is provided with a lip or projection 40 which extends downwardly at an angle across the upper end of the coin-chute S. Preferably, the projection 40, which is the closing portion of the gate 35, has an extension 41 adapted to enter a slot or recess 42 in the wall 43 of the coin-chute S. In this way the gate 43 effectively closes the mouth of the coin-chute S. Suitable spring means, such as the spring blade 44, normally holds the gate 35 in closing position. The spring 44 is at one end secured to the stud 45 on the supporting plate 37 and at its free end engages the pin 46 carried by the gate 35 near its front or upper end. If desired, the gate 35 may be provided with an upstanding flange 47 at its upper or front end to bear against the shoulder 48 of the notch or recess 49 formed in the outer edge of the supporting plate 37. The engagement of the flange 47 with the shoulder 48 limits the inward movement of the gate 35.

The locking or controlling member 36 is shown in the form of a slidable plate mounted on studs or pins 50 which project from the supporting plate 37 and engage in slots 51 in the slide 36. At its forward end the slide 36 is provided with a tooth 52 and a beveled recess 53. The gate 35 has a tooth 54 projecting from one side, said tooth being of a shape to engage the recess 53 of the slide 36 and thereby lock the gate 35 in normal or closing position when the parts are in their normal position, as shown in Fig. 1. Suitable spring means, such as the spring blade 55 secured at one end to the stud 56 on the supporting plate 37, is adapted to engage the slide 36 and normally impel it toward the gate 35. The slide 36 has a portion 57 which extends across one end of the coin-entrance slot of the machine. The coin-entrance slot is formed by the slot 3 in the top plate 2 and the aligned slot 3^a in the supporting plate 37.

The operation of the gate 35 and slide 36 is as follows: Normally the parts are in the position shown in Figs. 1, 2 and 3, from which it will be seen that the gate 35 is normally locked in closing position by engagement of the tooth 54 of the gate with the interlocking tooth 52 of the slide 36. This is clearly shown in Fig. 2. When a proper coin is inserted into the coin-entrance slot, the edge of the coin engages the obstructing portion 57 of the slide 36 and thus forces the slide outwardly (to the right, as viewed in Fig. 2), until the interlocking teeth 52 and 54 are out of engagement with each other. After the slide has been moved into unlocking position, the lower edge of the inwardly moving coin engages the beveled

or cam-shaped projection 40 of the gate 35 and forces the latter sufficiently into open position to allow the lower end of the coin to pass by the lowermost extension 41 of the gate 35. When the coin has been inserted about halfway, the gate 35 and slide 36 occupy the positions shown in Figs. 5, 6 and 7. It should be noted that in this position of the parts, the lower end of the gate 35 is still in frictional engagement with the face of the inserted coin C, as clearly shown in Fig. 7. Now, as the coin is pushed farther into the slot, the slide 36 is gradually impelled inwardly (toward the left, as viewed in Fig. 6) by the action of spring 55, until it reaches its normal position. However, as the slide 36 is thus moved from actuated back to normal position, the beveled surface 52^a of the tooth 52 engages the beveled edge 54^a of the tooth 54 and thus forces the gate 35 still farther into open position. This action takes place before the entire coin has been inserted through the coin-entrance slot. As soon as the gate 35 is thus moved into full open position by the slide 36, the extreme lower end 41 of the gate 35 is out of contact with the coin C and the latter is thus free to fall through the coin-chute S.

After the inserted coin has passed by the guard mechanism it falls down the coin-chute S into position between the lower edge 33 of the coin-chute and the stud 32 on the swinging gravity pawl 29, as previously explained in detail. When, therefore, the hand lever 23 is pulled down, the tripping bar 9 is moved downwardly a sufficient amount to trip the lower goods-supporting shelf 5. I make use of this movement of the bar 9 to restore the parts of the guard mechanism for the coin-chute into normal position. The bar 9 is at its upper end provided with a spring 58 having a forwardly extending head 59. On the stud 60 mounted conveniently within the casing is pivoted the lever 61 having an end 62 projecting into the path of the head 59 of the spring 58. The upper end of the lever 61 is formed with projections 63 and 64 adapted to engage in the slot or recess 65 of the slide 36. The normal position of the restoring lever 61 is that shown in Fig. 1, from which it will be seen that the projection 63 rests normally against the shoulder 66 of the recess 65 in the slide 36. When the bar 9 is pulled down to eject the first package, the spring head 59 engages the end 62 of the lever 61 and rocks the lever so that the projection 63 moves the slide 36 away from the gate 35. It should be remembered that when this actuation of the slide 36 takes place, the gate 35 is held locked in full open position by the slide 36, as shown in Fig. 8, and as the lever 61 moves the slide 36 away from the open gate 35, the

latter moves rearwardly into closing position under the action of spring 44. The engagement between the spring head 59 and the lever 61 is interrupted as the bar 9 continues its downward movement. In other words, after the lever 61 has been actuated by the spring head 59 into position to move the slide 36 into locking position to allow the gate 35 to move back into normal or closing position, continued downward movement of the bar 9 causes the spring head 59 to snap out of engagement with the projecting end 62 of the lever 61, thus leaving the lever in actuated position. As soon as the spring head 59 snaps past the projecting end 62 of the actuated lever 61 (which does not occur until after the gate 35 is back in normal or closing position), the spring 55 moves the slide 36 and with it the lever 61 back into normal position, as shown in Figs. 1 and 2. The parts are now reset and are ready to repeat the operation above described when the next coin is inserted.

The connection between the slide 36 and the coin-controlled bar 9 through the lever 61 is such that after the last package has been ejected the lever 61 locks the slide 36 in a position in which the gate 35 is unlocked and the coin-entrance slot sufficiently closed to prevent the insertion of proper coins into the machine. The bar 9 is at its upper end provided with an over-hanging flange 67 arranged in operative alignment with the end 62 of the restoring lever 61. When the bar 9 receives its final movement (which in the present instance occurs when the second package is ejected), the over-hanging flange 67 strikes the extending portion 62 of the lever 61 and rocks the lever to move the slide 36 into unlocking position. This operation of the restoring lever 61 and the slide 36 is precisely the same as when the spring head 59 actuates the lever 61. However, after the lever 61 has been operated by the flange 67, the lever is held in its operated position, as shown in Fig. 9. In this position of the lever 61 the projections 63 and 64 bear against the ends of the recess 65 in the slide 36 and thus lock the slide against movement in either direction. It will be seen that when the slide is in this locked position, the coin-engaging portion 57 thereof extends across one end of the coin-entrance slot sufficiently to prevent the insertion of a proper coin. Fig. 9 shows how the coin (indicated in dotted lines at C') is prevented from being inserted into the slot. In other words, when the machine is empty, the slide 36 acts as a slot-closer.

It will be observed that when the slide 36 is in slot-closing position, the gate 35 is in unlocked position. This gives to the gate the additional function of acting as an indicating device to the collector who comes to re-

plenish the machine and collect the coins therefrom. As the collector's time is valuable, it is of importance that he be enabled to determine as quickly as possible whether 5 a machine is empty and, therefore, needs refilling. With the mechanism above described, all that the collector has to do in order to determine whether a machine is empty or not, is to insert a flat metal strip 10 (say, about one-half of an inch wide and one-sixteenth of an inch thick) into the coin-slot of the machine. If the machine is empty, the strip will pass freely through, as the gate 35 is unlocked. But if there are 15 any goods left in the machine, the gate is positively locked by the slide 36 and the strip cannot, therefore, enter the slot. This affords a very quick and sure means of determining whether a machine needs attention. 20 This is of particular advantage in machines placed in theaters which are usually kept dark or semi-dark when collections are made.

To reset the parts after the machine has 25 been refilled, all that need be done is to shift the bar 9 back to its uppermost position. This will bring the spring head 59 into engagement with the extension 62 of the lever 61 and rock it back into the position shown 30 in Fig. 1. This will allow the slide 36 to move back into the position shown in Fig. 2.

It will thus be seen from the foregoing 35 that I have provided an exceedingly simple and efficient means for closing the mouth of the coin-chute so as to prevent the insertion of extraneous material (such as paper and the like) into the coin-chute. When the machine is empty and the gate 35 is in unlocked position during that period, it might be possible 40 to stuff paper or like material into the coin-chute S. To afford the ready removal of such extraneous matter when the machine is being replenished and reset, I provide the intermediate wall or partition 4 with openings 45 68 and 69 which are shaped generally to follow the zigzag contour of the coin-chute. It will be observed that the wall 4 constitutes the front wall of the coin-chute and the rear wall of the goods-magazine. If, as 50 will usually be the case, the machine casing is secured to the inclining back of a theater chair, a piece of paper inserted into the coin-chute would probably fall by gravity out of the openings 68 and 69 and in that way pass 55 through the goods chamber to the bottom plate 15. Should the inserted paper remain within the coin-chute, it can be very easily removed through the openings 68 and 69.

While I have above described a particular 60 form of construction, I would have it understood that I have done so merely by way of illustration and that the principle of my invention may be mechanically carried out in other ways than that shown and described.

Having thus described my invention what 65 I claim as new and desire to secure by Letters Patent of the United States, is:

1. In a coin-controlled machine, a casing 70 provided with a coin-entrance slot and a coin-chute leading therefrom, the walls of said casing about said slot being closed, a movable gate mounted in close proximity to said slot and normally closing said coin-chute, and a movable member mounted independently of said gate for normally locking 75 said gate in closing position, said member being moved into unlocking position by the entering coin, whereby the coin engages the unlocked gate and moves it into open or unobstructing position, said gate being mounted 80 to operate in a direction substantially at right angles to the plane of movement of the entering coin.

2. In a coin-controlled machine, a casing 85 provided with a coin-entrance slot and a coin-chute leading therefrom, the walls of said casing about said coin-slot being closed, a movable gate mounted in close proximity to said slot and normally closing said coin-chute, and a spring-pressed slide mounted 90 independently of said gate for normally locking said gate in closing position, said slide having a portion adapted to be engaged by the edge of the entering coin which moves the slide into unlocking position, 95 whereupon the coin engages the unlocked gate and moves it into open or unobstructing position.

3. In a coin-controlled machine, a casing 100 provided with a coin-entrance slot and a coin-chute leading therefrom, a movable gate mounted in close proximity to said slot and normally closing said coin-chute, a movable member for normally locking said gate in closing position, said member being moved 105 into unlocking position by the entering coin, whereupon the coin engages the unlocked gate and moves it into open or unobstructing position, and coöperating means on said gate and said member whereby the latter on being released by the entering coin moves said gate still farther into open position to clear the coin-chute for the free passage of the coin. 110

4. In a coin-controlled machine, a casing 115 provided with a coin-entrance slot and a coin-chute leading therefrom, a movable gate mounted in close proximity to said slot and normally closing said coin-chute, a spring-pressed slide for normally locking said gate 120 in closing position, said slide having a portion adapted to be engaged by the edge of the entering coin which moves the slide into unlocking position, whereupon the coin engages the unlocked gate and moves it into 125 open or unobstructing position, and coöperating means on said gate and said slide whereby the latter on being released by the

entering coin moves said gate still farther into open position to clear the coin-chute for the free passage of the coin.

5. In a coin-controlled machine, a casing provided with a coin-entrance slot and a coin-chute leading therefrom, a movable gate mounted in close proximity to said slot and normally closing said coin-chute, a movable member for normally locking said gate in closing position, said member being moved into unlocking position by the entering coin, whereupon the coin engages the unlocked gate and moves it into open or unobstructing position, coöperating means on said gate and said member whereby the latter on being released by the entering coin moves said gate still farther into open position to clear the coin-chute for the free passage of the coin, said member locking said gate in its final open position, mechanism adapted to be operated through the medium of the deposited coin, and means whereby the operation of said mechanism causes movement of said member into position to release said gate, so that said gate automatically moves back to normal or closing position, whereupon said member automatically moves into normal position to lock said gate in closing position.
- 30 6. In a coin-controlled machine, a casing provided with a coin-entrance slot and a coin-chute leading therefrom, a movable gate mounted in close proximity to said slot and normally closing said coin-chute, a movable member for normally locking said gate in closing position, said member being moved into unlocking position by the entering coin, whereupon the coin engages the unlocked gate and moves it into open or unobstructing position, coöperating means on said gate and said member whereby the latter on being released by the entering coin moves said gate still farther into open position to clear the coin-chute for the free passage of the coin, said member locking said gate in its final open position, mechanism adapted to be operated through the medium of the deposited coin, an actuating element for moving said member into unlocking position, and means connected with said mechanism for operating said element to release said gate when said mechanism is operated, said released gate automatically returning to normal or closing position, whereupon said member automatically moves into normal position to lock said gate in closing position.

7. In a coin-controlled machine, a casing provided with a coin-entrance slot and a coin-chute leading therefrom, a movable gate mounted in close proximity to said slot and normally closing said coin-chute, a movable member for normally locking said gate in closing position, said member being

moved into unlocking position by the entering coin, whereupon the coin engages the unlocked gate and moves it into open or unobstructing position, coöperating means on said gate and said member whereby the latter on being released by the entering coin moves said gate still farther into open position to clear the coin-chute for the free passage of the coin, said member locking said gate in its final open position, mechanism adapted to be operated through the medium of the deposited coin into a plurality of successive positions, means whereby each operation of said mechanism causes movement of said member into position to release said gate, so that said gate automatically moves back to normal or closing position, whereupon said member automatically moves into normal position to lock said gate in closing position, and means whereby said member is locked in position to release said gate and at the same time close said coin-entrance slot when said mechanism is in its final operated position.

8. In a coin-controlled machine, a coin-chute guard comprising a pair of movable members arranged near the coin-entrance slot, one of said members normally closing the coin-chute, the other member normally locking said first mentioned member in closing position, said members being so constructed and arranged relatively to each other that the entering coin first moves said second member into unlocking position and then moves said unlocked closing member partially into open position, whereupon said second member is sufficiently released by the entering coin to move the other member into full open position for the free passage of the coin through the chute.

9. In a coin-controlled vending machine, a casing provided with a magazine and a coin-entrance slot, mechanism adapted to be operated through the medium of the deposited coin to eject the packages from said magazine, a guard member arranged near the coin-entrance slot to normally close the coin-chute, a controlling member associated with said guard member and adapted to normally lock said guard member in closing position, said controlling member being moved into releasing position by an entering coin, and means for automatically locking said controlling member in position to unlock said guard member and to obstruct said coin-entrance slot against the insertion of proper coins when said magazine is empty.

10. In a coin-controlled vending machine, a casing provided with a coin-entrance slot, a magazine for the vendable articles, coin-controlled mechanism for ejecting the articles from said magazine, a normally locked member arranged at said slot for normally

closing or obstructing the same, means whereby the entering coin automatically unlocks said member, and means whereby said member remains in unlocked position when 5 said magazine is empty.

11. In a coin-controlled machine, a casing provided with a coin-entrance slot, a normally locked member arranged at said slot and adapted to be automatically unlocked 10 by the entering coin, said member frictionally engaging one face of the partly inserted coin, and means controlled by the coin whereby the further insertion of the coin automatically removes said member from 15 fractional engagement with the coin and allows free passage of the coin through said slot into the machine.

12. In a coin-controlled machine, a casing provided with a coin-entrance slot in one of 20 its walls, a movable gate mounted on said wall within the casing and normally closing or obstructing said slot, and a movable member also mounted on said wall within the casing for normally locking said gate in 25 closing position, said member projecting across one end of the coin-slot to be engaged by the edge of the entering coin and actuated into unlocking position, whereupon the coin engages the unlocked gate and moves 30 it into open or unobstructing position.

13. In a coin-controlled machine, a casing provided with a coin-entrance slot in one of 35 its walls, a movable gate mounted on said wall within the casing and normally clos-

ing or obstructing said slot, and a slidable 35 plate also mounted on said wall within the casing for normally locking said gate in closing position and movable in a plane substantially parallel with said wall, said slide projecting across one end of the coin-slot to be engaged by the edge of the entering coin and actuated into unlocking position, whereupon the coin engages the unlocked gate and moves it into open or unobstructing 40 position.

14. In a coin-controlled machine, a casing provided with a coin-entrance slot in one of its walls, a slidable gate mounted on said wall within the casing and normally closing or obstructing said slot, said gate being 50 movable in a plane substantially parallel with said wall, and a slidable plate also arranged on said wall within the casing for normally locking said gate in closing position and movable in a plane substantially parallel with said wall, said slide projecting across one end of the coin-slot to be engaged by the edge of the entering coin and actuated into unlocking position, whereupon the coin engages the unlocked gate and shifts it 55 into open or unobstructing position.

In witness whereof I hereunto subscribe my name this 3rd day of February, 1916.

ALBERT D. GROVER.

Witnesses:

FLORENCE E. LANG,
MARY A. LYONS.
